UNITED STATES PATENT OFFICE.

GEORGE C. SNYDER, OF NEW YORK, N. Y., ASSIGNEE TO WILLIAM H. DAVIS, TRUSTEE,
OF NEW YORK, N. Y.

HOLLOW WARE

1,270,891.

Specification of Letters Patent.

Patented July 2, 1918.

Application filed July 23, 1917. Serial No. 182,168.

To all whom it may concern:

Be it known that I, GEORGE C. SNYDER, a citizen of the United States, residing at New York city, in the county of New York, State of New York, have invented certain new and useful Improvements in Hollow Ware; and I do hereby declare the following to be a full, clear, and exact description of the invention, such as will enable others skilled in the art to which it appertains to make and use the same.

The present invention relates to hollow articles such as barrels, kegs, cartons, pails, tubs and the like. While the articles may find their widest field of use as containers and receptacles for all purposes, the invention is not limited to articles of this nature but is intended to include tubular structures adapted for a wide variety of uses especially in the manufacture of furniture and similar articles.

Heretofore, containers have been made of paper or container-board formed in the shape of drums and sometimes reinforced by hoops. Containers of this general type with slight modifications have gone into extensive use in sizes ranging from small mailing tubes up to receptacles having a capacity of several gallons, but so far as I am aware it has never been possible to give to any of these containers the correct shape of a barrel having an arch or bilge midway between the ends. It is almost essential in the case of barrels designed to carry heavy

loads that they be formed in this shape in order to obtain the strength of the arched or bilged portion as well as to permit of their being easily turned up on end or conveniently directed in their course when rolled along. It has also been impossible to make tapered pails, tubs and similar articles out of paper or like materials except by a process of molding pulp when in a softened condition and thereafter allowing it to harden and by treating it with impervious substances to render the articles water-proof, or by cutting out a paper blank adapted to form a tapered pail shell when the extremities of the blank are brought together and fastened by rivets or otherwise.

The latter construction involves a seam running parallel to the axis of the pail and this is objectionable as the seam may open when the pail is used.

It is an object of the present invention

to produce hollow articles composed of a strip or strips of suitable material wound in a series of overlapping convolutions which are united to each other to form in effect a substantially integral structure. The articles may then be treated with any suitable substance to render them impervious to the action of any liquids or other materials which it is intended they shall contain.

The articles may be formed at a minimum cost and a wide variety of substances may be used for their formation as, for instance, metallic strips and mineral fibers such as asbestos, or cheaper kinds of material such as the common forms of vegetable fiber, such as the pulp of wood, straw, or any other appropriate substance, the only requirement being that the material must be capable of being formed into ribbons or webs, and preferably the material, if paper, should be practically free from sizings, fillers and the finishing substances generally found in commercial papers.

The articles of the present invention may be constructed of material which has been previously coated with a suitable, solidified or dried adhesive which is moistened just prior to the operation of forming the article. By means of this method the strips of material may be wound rapidly and hence the finished article may be produced in considerably less time than is required to make similar articles by the methods at present in common use.

In the case of many containers, and particularly barrels, the heads are applied after the body of the barrel has been formed and the present invention meets this manufacturing practice by forming articles with comparatively thick chimes into which the heads may be driven and retained in place by glue or in any other manner.

Among the many kinds of articles included within the scope of the present invention, a few typical ones are illustrated in the accompanying drawings in which Figure 1 shows an exterior view of a barrel; Fig. 2 is a view in longitudinal cross section of the same article; Fig. 3 is an exterior view of another form of barrel showing the effect of varying the overlap of the convolutions; Fig. 4 is a view of a hollow tubular member adapted for use in furniture or similar articles; Fig. 5 is an exterior view of a modified form of barrel or container;

and Fig. 6 is a view in cross section of a portion of the end of an article showing the relation of the successive windings.

It is intended that the articles shown herein shall be produced upon a machine like that shown in my co-pending application, Serial Number 182166, filed July 23, 1917, and in accordance with the processes covered in my co-pending application, Serial Number 182,167 filed July 23, 1917. It will be understood, however, that the articles may be formed on machines other than of the particular form disclosed in these applications provided such machines are adapted to give the articles the required structural features.

These structural features are, in the case of the barrel shown in Fig. 2, the provision of a number of super-imposed convolutions or inner cylindrical bands making up the chimes of the barrel as indicated at 10. These two chimes are made by partially slitting a band of material into two strips and then winding the strips upon suitable mandrels as described at length in the applications referred to above. The intermediate portions 11 of the barrel comprise oppositely directed elongated spirals each formed by a series of convolutions each of which is slightly displaced with respect to the preceding one but partially overlaps the same, so that the diameter of the barrel increases gradually toward the central or bilge portion 12. In order to give this portion of the barrel additional strength, a number of convolutions of material are wound about the central portion, and the material while it is being wound at this stage of the operation is not slit as it is when forming the chimes and the intermediate portions. The finished article appears on the outside as shown in Fig. 1 and may be painted or otherwise covered as desired. If it is intended to be used for holding liquids which may penetrate the material of which it is formed, it may be coated on the inside with suitable material to render it impervious to these liquids. When the article is formed of strips of material which have been previously coated with adhesive and are moistened just prior to the formation of the article, the convolutions thereof become firmly united to each other when the adhesive has hardened and the result is a structure which possesses maximum strength, but is of comparatively light weight.

Another form of barrel is shown in Fig. 3, and in this case the end portions as indicated at 13 are formed by winding the convolutions with a relatively slight amount of longitudinal displacement so that the wall of the article is thicker and the inclination of the outer surface is steeper. At the point indicated by 14 the ratio of longitudinal to winding movement is changed so

that the convolutions are spaced apart to a greater extent than at the portion 13, and the sides of the article approach more nearly a cylindrical form. The portion 15 of the article is a bilge formed by winding the strip of material without any displacement and corresponds to the bilge portion 12 of the article shown in Figs. 1 and 2.

Fig. 4 represents a modification of the invention in which the article produced is comparatively long and may be used as a chair round or for other purposes. This form of the article has all of the strength which characterizes a tube and at the same time has the additional strength provided by the tapering, overlapping construction of the end portions 16 and the bilge portion 17 at the center.

For the purpose of holding many substances of light weight, containers of the shape shown in Fig. 5 may be used. These containers are formed by a winding operation in which the convolutions are spaced apart considerably more than in the case of the articles shown in the preceding figures. The result is that while the articles shown in Fig. 5 have not the thickness nor the strength of the other articles, they will nevertheless be sufficient for many purposes and may be cheaply produced upon the machines shown in my co-pending application, Serial Number 182,166, especially Fig. 11.

Fig. 6 represents in cross section a portion of the end of one of the articles showing the relation of the convolutions which make up the chime of a barrel or the bottom of a pail and also the spaced relation of a number of the convolutions making up the body of the article.

The articles described above and illustrated in the drawings are but a few examples of the many possible articles which the invention contemplates. As has been explained above, the articles may be formed of any kind of material ranging from metallic strips or mineral fibers such as asbestos to the commonest forms of vegetable fiber such as wood pulp, the only requirement being that the material must be capable of being formed into ribbons or webs of considerable length and should preferably be free from substances that do not add strength.

In the case of any of the articles of the present invention, the strength of the article results in a considerable degree from the fact that the shell of the article is formed of a series of tightly overlapped convolutions of continuous material, while in the case of an ordinary keg or barrel made up of staves and hoops the former add nothing to the circumferential strength of the article which is dependent upon the strength of the hoops and thus limited.

For many purposes, such, for instance,

as in the oil trade, it is customary to spray the inside of the containers with hot glue after the heads have been inserted. All of the articles of the present invention may be thus treated either during the process of manufacture or after they have been completed. Any suitable substance for treating the inside of the article to make it resist the action of the liquid which is to be contained therein, may be applied to the material of which the article is formed.

By using wood pulp paper or container-board, it is possible to bake the articles at temperatures that would be destructive to natural wood articles. Durable and lustrous coatings in suitable colors may thus be baked on the surfaces of the articles which thus become in effect enamelware possessing the sanitary and heat-resisting advantages of such vessels.

What I claim is:

1. A new article of manufacture comprising a hollow article which consists of a strip of material divided into two parts which are wound into the form of oppositely directed spirals with the convolutions thereof displaced out of the normal planes of the spirals and a strip of undivided material wound about the meeting ends of the spirals to join them together.

2. A new article of manufacture comprising a hollow article consisting of material wound in spirals in single planes with other portions of the material wound in oppositely directed spirals having their successive convolutions axially displaced with respect to each other, and other portions of material joining the axially displaced convolutions to each other.

3. A new article of manufacture comprising a hollow article consisting of a strip of material divided into two parts which are wound in the form of a pair of inner cylindrical bands and having other windings in the form of axially displaced convolutions and a third portion in the form of a cylindrical undivided strip wound about the adjacent portions of the second named windings to join them together.

4. A new article of manufacture comprising a hollow article consisting of a plurality of integral portions of material wound in spiral form with the convolutions thereof displaced, with respect to each other, in opposite directions; said spirally wound portions being joined by a band of the material wound with non-displaced convolutions.

5. A new article of manufacture comprising a hollow article consisting of a band of material slit into a plurality of strips wound in the form of oppositely directed separated spirals and having a band of non-slit material wound about the adjacent regions of the spirally wound portions of the article to join the same together.

6. A new article of manufacture comprising a hollow article consisting of a plurality of superimposed convolutions forming the ends of the article, intermediate portions formed of spirally-wound strips of material having their convolutions displaced with respect to each other, and a central portion formed of the same material wound in a plurality of superimposed convolutions to join the spirally wound portions to each other and to form a reinforcing band about the center of the article.

7. A new article of manufacture comprising a hollow article consisting of end portions formed of strips of divided material wound into convolutions with matched edges, a body portion formed of the strips of material wound into oppositely tapering convolutions having spaced edges and a central joining portion formed of a strip of undivided material wound into convolutions having matched edges.

8. A new article of manufacture comprising a hollow article consisting of strips of divided material wound into convolutions forming end reinforcements, oppositely directed spirally wound convolutions forming a body portion and other convolutions of undivided material forming an outer central reinforcement and joining the parts of the body portion together.

9. A new article of manufacture comprising a hollow article consisting of a plurality of matched wound convolutions forming the ends of the article and oppositely directed spirally wound tapered portions between and integral with the ends and a central reinforcing band integral with the spirally wound portions and joining the same together.

10. A new article of manufacture, comprising a hollow article consisting of a plurality of wound portions forming the ends of the article, spirally-wound tapered portions between and integral with the end portions, and a central portion integral with the tapered portions and forming a band about the center of the article.

11. A new article of manufacture, comprising a hollow article consisting of a plurality of oppositely directed convolute sections connected together by an intermediate portion composed of matched overlapping convolutions.

12. A new article of manufacture comprising a hollow article consisting of strips of material wound convolutely to form inner reinforcing bands, spirally wound body portions and another convolutely wound portion in which strips are united to form an outer reinforcing band about the central portion of the article.

13. A new article of manufacture, comprising a hollow article consisting of a plurality of oppositely directed convolute sec-

tions connected together by an intermediate portion.

14. A new article of manufacture, comprising a hollow article consisting of a plurality of oppositely directed convolute sections of material connected together by an intermediate portion of the same material.

15. A new article of manufacture, com-

prising a hollow article consisting of a plurality of oppositely directed convolute sections of strip material connected together by an intermediate portion formed as a continuation of the same material.

In testimony whereof I affix my signature.

GEORGE C. SNYDER.
